UNITED STATES PATENT OFFICE.

EDMOND W. T. RICHMOND, OF ROMFORD, ENGLAND.

DESIGN FOR A GAS-STOVE.

SPECIFICATION forming part of Design No. 33,925, dated January 15, 1901.

Application filed December 19, 1900. Serial No. 40,450. Term of patent 14 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the base portion A, having the feet *a* and the sloping ornamented top *a'*, the vertical outside columns B, the central columns C, of smaller width than the outside columns, the top portion D, projecting laterally from the tops of the columns and having the molded

edges *d*, the open-work top *d'*, the opening or cavity E below the central columns, and the front plate F above the cavity, having the central ornamentation *f*, surrounded by foliated ornamentations *f'*. The columns are polygonal, each having a series of flat vertical ornamented facets, and there are vertical spaces between the columns.

I claim—

The design for a gas-stove, substantially as shown and described.

In testimony whereof I have hereunto subscribed my name.

EDMOND W. T. RICHMOND.

Witnesses:

KATHARINE MACMAHON,
EDWARD C. DAVIDSON.
